PLANER TYPE MILLING MACHINE WITH CENTER HEAD

Graham E. Marx, Cincinnati, Ohio, assignor to The G. A. Gray Company, Cincinnati, Ohio, a corporation of Ohio

Filed Dec. 17, 1964, Ser. No. 418,986
10 Claims. (Cl. 90—15)

This invention relates to a planer type milling machine provided with a center head which is arranged for movement transverse the planer bed on a cross rail, the cross rail itself being arranged for vertical movement on the columns of the machine.

It often happens that in the machining of certain articles and particularly the drive members on the ends of steel rolling mill rolls, that it is desirable to do machining work on a planer type milling machine which cannot be accomplished by means of a tool secured to either of the spindles of the conventional side heads.

It has, therefore, been the practice to provide an attachment which could be bolted to the side head on one of said columns, with a telescoping bridge arranged to be secured to the side head on the opposite column, and such attachment was arranged to be driven from the spindle in one of the side heads. Such attachments have been subject to various objections, the principal ones being that the bridge between the columns has not been sufficiently rigid but more importantly that the change-over, involved in picking up the attachment, positioning it, securing it in place, has averaged hours of time. Much time is usually lost in waiting for a crane and in order to make the attachment as rigid as possible, a great many bolts were provided and therefore the machine usually had about two hours down time before the attachment was in position, properly secured and ready for use.

With the foregoing considerations in mind, it is an object of the present invention to provide a device which will do everything of which the conventional attachment was capable but which can be placed in operative position or removed from operative position out of the way in not more than a few minutes. Further objects include the provision of such an apparatus which will be extremely rigid and therefore capable of transmitting far greater horse power than was possible with the conventional attachment and which is provided with safety devices such that the danger of a drop are entirely eliminated.

These and other objects of the invention which will be described in more detail hereinafter or which will become apparent to one skilled in the art upon reading these specifications are accomplished by that certain construction and arrangement of parts of which the following describes an exemplary embodiment.

Reference is made to the drawings forming a part hereof and in which:

FIG. 1 is a front elevational view of a planer type milling machine having the center head of the present invention.

FIG. 2 is a fragmentary plan view of the cross rail.

FIG. 3 is a fragmentary front elevational view of the cross rail.

FIG. 4 is a fragmentary rear elevational view of one end of the cross rail.

FIG. 5 is a cross sectional view taken on the line 5—5 of FIG. 3.

FIG. 6 is a fragmentary plan view of the cross rail, a column and a side head showing the pin mechanism in one position.

FIG. 7 is a view similar to FIG. 6 showing the pin mechanism in its other position.

FIG. 8 is a fragmentary cross sectional view taken on the line 8—8 of FIG. 6.

2

FIG. 9 is a cross sectional view on a considerably enlarged scale of the center head, taken on the line 9—9 of FIG. 1.

FIG. 10 is a cross sectional view taken on the line 10—10 of FIG. 9.

FIG. 11 is a fragmentary rear view of the machine showing the cross rail and center head as seen from the rear of the machine.

FIG. 12 is an enlarged front elevational view of the center head; and

FIG. 13 is an elevational view of the same as seen from the left of FIG. 1.

Briefly, in the practice of the invention the planer type milling machine may be in all respects an entirely con-

ventional machine having a table which is reciprocable along ways and having at each side of the bed a fixed column and having a side head arranged for vertical movement on each column along ways on the column under the influence of lead screws on the column engag-

ing nuts in the respective side heads. The lead screws may be coupled together so that the two side heads may be caused to move in exact synchronism. Each side head is provided with a quill which may be advanced and re-

tracted and in each said quill is a spindle to which a suit-
able tool may be attached. As is well known, when the spindle in such a side head rotates, the cutting tool is caused to rotate and the feed may be in a horizontal di-
rection by movement of the table to which the work piece is secured, or in a vertical direction by vertical movement of the side head and in a transverse direction by advance-
ment or retraction of the quill. All of the foregoing is in every respect conventional and well known and does not constitute a part of the present invention.

According to the present invention, such a machine is provided with a cross rail extending between the columns and arranged to move in a vertical direction along said

columns and the cross rail is provided with a center head which is freely movable transversely of the bed of the machine along the cross rail. Means are provided on the center head for the attachment of cutting elements on the front or on the rear or on the bottom of the center head.

The cross rail is provided with a pin mechanism by means of which it may be selectively pinned or secured to the two columns in its uppermost out of the way position, or

pinned and thus secured to the two side heads when they are brought to their uppermost position in synchronism. When the cross rail has thus been pinned to the two side heads and freed from the columns, it will of course move upwardly and downwardly along the columns

with the side heads as they are caused to move upwardly and downwardly on the columns. The center head is provided with coupling means whereby it may be connected to the spindle in one of the side heads by ad-

vancing the quill in said side head so that transverse movement of the center head along the cross rail is accom-
plished by causing the respective quill to ad-

vance or retract and the coupling device is geared to one or more spindles whereby rotation of the side head spindle is transmitted to the center head spindles. By

means of the center head spindles, surfaces transverse to the bed and table of the machine may be machined or holes bored parallel to the length of the table and horizontal surfaces may be machined or vertical holes bored.

Referring now in more detail to the drawings and particularly to FIG. 1, the conventional planer type milling machine will be described only insofar as it is necessary to an understanding of the present invention. This machine will conventionally be provided with a bed 10 upon which a table 11 is arranged to reciprocate. On each side of the bed and table there is provided a column 12. On each column there is

70

provided a side head 13. Each column is provided with a lead screw 14 which engages a nut (not shown) within the respective side head so that as the lead screw rotates, the side heads are caused to move up and down. These side heads are counterbalanced by means of the cables 15 running over the sheaves 16 and provided with counterweights (not shown) as is conventional. In each spindle there is a quill 17 and in each quill there is a spindle 18. Various electric motors are provided for rotating the spindles 18 at appropriate speeds and under the influence of control levers the quills 17 may be caused to advance or retract at suitable speeds. The table is reciprocated in a conventional manner. The lead screws 14 through gearing (not shown) are connected to the shafts 19, which shafts 19 may be connected or disconnected by clutch mechanism within the casing 20, whereby the heads 13 may be caused to move individually, that is, one without the other, or whereby the two heads may be brought to their uppermost position and upon operation of the clutching mechanism, the two heads may be caused to move in exact synchronism.

The apparatus thus far described may in all respects be entirely conventional and will not be described further since the details do not form any part of the present invention.

According to the present invention, the machine is provided with a cross rail 21. This cross rail, as best seen in FIG. 5, is a hollow box-like weldment and is provided with a plurality of webs 22 for strengthening the cross rail beam and the webs 22 may be provided with openings 23 to reduce weight. A plurality of gusset plates 24 are also provided for additional strength.

The columns are provided with ways 25 along which the cross rail may travel and the usual retainers 26 are provided to keep the cross rail in engagement with the ways on the column.

At the top of the cross rail there are provided the pins 27 which are axially aligned, one of which is connected at its inner end to a piston within the cylinder 28, and the other of which is connected to the cylinder, as at 27a. By admitting hydraulic fluid to one side of the piston, the two pins 27 are forced apart (the piston moving in one direction and the cylinder in the other direction). To retract the pins, hydraulic pressure is applied to the other side of the piston and thereby the pins 27 are retracted (the piston and cylinder returning to their original position). It will be understood that suitable flexible hose connections (not shown) are provided, leading to the cylinder 28 at its two ends. The pins are arranged when the cross rail is in its uppermost position to enter apertures 31 in the columns 12. In this manner the cross rail is pinned to the columns in its uppermost out of the way position. The pins 27 may be provided with the large ends 32 so that when the pins are advanced to the position shown in FIG. 7, the enlarged portions 32 thereon serve as a safety to prevent withdrawal of the pins until the cross rail is elevated slightly and this can only be done when the cross rail is coupled to the side heads as described hereinafter.

The cross rail is provided with an additional pair of pins 33 and the pins 33 are adapted to engage in apertures 34 in the side heads 13. Each pin 27 is connected to the respective pin 33 by a link 35 pivoted at its center as at 36 and engaging a pin 37 on the pin 27 and a pin 38 on the pin 33. It will now be clear that if the pins 27 are advanced into engagement with the columns 12, the pins 33 are withdrawn from the side heads 13. This position is shown in FIG. 7 and with the parts in the position of FIG. 7 the side heads may be moved away leaving the cross rail and center head out of the way at the top of the columns. When it is desired to use the cross rail and center head, the two side heads are moved up to their uppermost position and fluid is supplied to the ports 30 of the cylinder 28 to retract the pins 27 and advance the pins 33. It will be noted that the pin 27 will enter

the column 12 before the pin 33 is released from the side head 13 and similarly it will remain engaged with the column until after the pin 33 engages the side head. In this way there is no danger that the cross rail and associated parts will drop. Blocks 21a are secured to the side heads 13 (FIG. 11), to support the weight of the cross rail, so that there will be no weight on the pins 27 and 33 when they are shifted.

The center head is indicated generally at 40 and is arranged to ride along ways 41, 42 and 43 on the cross rail 21. The center head is provided with a spindle extending horizontally from front to rear and indicated generally at 44 and a spindle extending vertically downward and indicated generally at 45. It is also provided with a drive shaft 46 (FIG. 10) which may have the tapered configuration 47 of a milling cutter so that the drive shaft 46 may be connected to the spindle of one of the side heads 13, as shown in FIG. 1 in broken line, and held in position by the usual draw bar arrangement 48. As will be seen from FIGS. 9 and 10, the spindle 46 has secured to it a bevel gear 49 which meshes with a bevel gear 50. The bevel gear 50 is keyed onto the spindle 44. The spindle 44 carries another bevel gear 51 which meshes with a bevel gear 52 secured to the spindle 45.

With the foregoing description in mind, it will now be clear that if the cross rail and center head are in their uppermost out of the way position shown in solid lines in FIG. 1, with the cross rail pinned to the two columns as shown in FIG. 7, if it is then desired to attach the cross rail and center head to the side heads for use, the following operations are performed. If the side heads are not coupled in synchronism, they are both run up to their uppermost position and then coupled so as to be in synchronism. The pin mechanism is then actuated to advance the pair of pins 33 and retract the pair of pins 27. In this way the cross rail is secured to the side heads and freed from the columns. The quill 17 of the appropriate side head is advanced until the tapered element 47 of the drive shaft 46 of the center head 40 is brought into engagement with the spindle 18 in said side head and the drive shaft 46 is secured to the spindle by the conventional draw bar arrangement 48. The center head is now ready for use in that rotation of the spindle 18 produces rotation of the spindles 44 and 45 and it will be clear that cutting elements may be attached to either end of the spindle 44 or to the spindle 45 as desired. The center head may be caused to feed transversely of the table, i.e. along the cross rail by advancing or retracting the quill 17 and the center head may be caused to feed in a vertical direction by movement in synchronism of the side heads. It will be understood that suitable clamps (not shown) and associated control devices (not shown) are provided to clamp the cross rail to the columns when taking a cut with the center head. These clamps are arranged in conventional manner to operate automatically when the direction selector switch controlling the side heads is in the neutral position.

When it is desired to return to conventional operation, it is only necessary to run the side heads up to their uppermost position and actuate the pin mechanism to move from the position of FIG. 6 to the position of FIG. 7 and to disconnect the draw bar 48 and retract the quill 17 to clear the spindle 46. The side heads may then be lowered and the machine may be used in its conventional way with the cross rail and center head left in their uppermost out of the way position. As mentioned above, it requires only a few minutes to attach the center head for use or to dispose it out of the way. It is not necessary to wait for a crane to be available and the usual jockeying of an attachment into position is entirely avoided.

It will of course be understood that the side heads are counterbalanced as by means of two cables 15 running over the pulleys 51 but this is conventional practice.

It will be clear that various modifications may be made without departing from the spirit of the invention.

I claim:

1. In a planer type milling machine having a bed, and a column at each side of said bed, each said column having a side head arranged for vertical movement on the respective column by means of a nut in each side head in engagement with a lead screw in the respective column, and said lead screws being arranged to be coupled together to cause said side heads to move in synchronism, and each of said side heads carrying a quill arranged for movement toward and away from the opposite column, and a spindle rotatable in each of said quills; a cross rail mounted for vertical movement on ways on said columns, a center head mounted for horizontal movement on ways on said cross rail, said center head having at least one rotatable spindle, said cross rail being arranged to be secured to said columns in its uppermost position out of the way, and also being arranged to be secured to said side heads upon release from said columns, and means for coupling the spindle of one of said side heads to the spindle of said center head, whereby said center head is moved in a vertical direction by movement of said side heads in a vertical direction, and in a horizontal direction by movement of the quill of said one of said side heads, and the spindle of said center head is caused to rotate by rotation of the spindle in said one of said quills.

2. The apparatus of claim 1, wherein said center head is provided with three spindles, two of said spindles being disposed on a horizontal axis parallel to said bed and oppositely directed, and the third spindle being disposed on a vertical axis and downwardly directed, all of said spindles being interconnected by gearing, whereby when said center head is secured to said side heads and connected to the spindle in said one of said side heads, all three spindles rotate and a cutting tool may be secured to any one or more of said spindles.

3. The apparatus of claim 1, wherein said cross rail is provided with a first pair of oppositely directed pins, and said columns adjacent the upper ends thereof are provided with sockets into which the respective pins of said first pair may enter when said cross rail is in its uppermost, out of the way position, and means for projecting said pair of pins into column-engaging position and retracting them from column-engaging position, said cross rail having a second pair of oppositely directed pins, and each of said side heads having a socket into which the respective pins of said second pair may enter when said side heads, in synchronism, are brought to their uppermost position, said pairs of pins being interconnected such that projection of said first pair produces retraction of the second pair, and vice versa, the pins of said first pair being longer than those of said second pair, whereby said cross rail remains secured to said columns until it is secured to said side heads, and is secured to said columns before it is released from said side heads.

4. The apparatus of claim 3, wherein the means for projecting said first pair of pins into column engaging position and retracting them therefrom comprises a cylinder and a piston in said cylinder, the piston being connected to one pin of said first pair and the cylinder being connected to the other pin of said first pair, and means for applying hydraulic pressure to said cylinder on one side of said piston while venting said cylinder beyond said piston, and for applying hydraulic pressure to the other side of said piston while venting the cylinder on said one side.

5. The apparatus of claim 3, wherein the interconnec-

tion between said pairs of pins comprises two substantially centrally pivoted levers, one connected at one of its ends to one of the pins of said first pair and at the other end to one of the pins of said second pair, the other of said levers being connected at one of its ends to the other pin of said first pair, and at its other end to the other pin of said second pair.

6. A planer type milling machine having two columns, a side head on each of said columns, a quill in each side head and a spindle in each quill, and a cross rail freely movable vertically on ways on the respective columns and securable selectively to said columns in an out of the way position, and to said side heads for vertical movement therewith, a center head freely movable horizontally on ways on said cross rail and having at least one spindle, and means for coupling said center head spindle to one of said side head spindles for movement of said center head horizontally with the respective quill and for rotation with the respective side head spindle.

7. A machine according to claim 6, wherein said center head is provided with three spindles, two of said spindles being disposed on a horizontal axis transversely of said cross rail and oppositely directed, and the third spindle being disposed on a vertical axis and downwardly directed, all of said spindles being interconnected by gearing.

8. A machine according to claim 6, wherein said cross rail is provided with a first pair of oppositely directed pins, and said columns adjacent the upper ends thereof are provided with sockets into which the respective pins of said first pair may enter when said cross rail is in its uppermost, out of the way position, and means for projecting said pair of pins into column-engaging position and said cross rail having a second pair of oppositely directed pins, and each of said side heads having a socket into which the respective pins of said second pair may enter when said side heads, in synchronism, are brought to their uppermost position, said pairs of pins being interconnected such that projection of said first pair produces retraction of the second pair, and vice versa, the pins of said first pair being longer than those of said second pair, whereby said cross rail remains secured to said columns until it is secured to said side heads, and is secured to said columns before it is released from said side heads.

9. A machine according to claim 8, wherein the means for projecting said first pair of pins into column-engaging position and retracting them therefrom comprises a cylinder and a piston in said cylinder, the piston being connected to one pin of said first pair, and the cylinder being connected to the other pin of said first pair, and means for applying hydraulic pressure to said cylinder on one side of said piston while venting said cylinder beyond said piston, and for applying hydraulic pressure to the other side of said piston while venting the cylinder on said one side.

10. A machine according to claim 8, wherein the interconnection between said pairs of pins comprises two substantially centrally pivoted levers, one connected at one of its ends to one of the pins of said first pair and at the other end to one of the pins of said second pair, the other of said levers being connected at one of its ends to the other pin of said first pair, and at its other end to the other pin of said second pair.
